[57] ABSTRACT

An electronic timepiece with a time signalling device wherein to the time signalling device is applied an output signal with a predetermined frequency which is produced from one of a plurality of cascade connected, bistable multivibrator stages in a divider which is used for dividing a high frequency signal into a standard time signal of low frequency. Further, a plurality of output signals produced from the corresponding stage are periodically and alternately applied to the time signalling device for enhancement of the tone of the time signalling sound.

FIG. 3

ELECTRONIC TIMEPIECE WITH A TIME SIGNALLING DEVICE

FIELD OF INVENTION

The present invention relates to an electronic time-piece with a signalling device, and more particularly to an electronic timepiece with a time signalling device adapted to produce a comfortable time signalling sound at a set time with accurate time intervals.

BACKGROUND OF INVENTION

Conventional time signalling devices used with a time-piece have been of such a type that they are provided with an electric bell actuated at a set time or with an alarm device operated for producing alarm sounds.

These devices, however, have had drawbacks in that they could not produce time signalling sounds at accurate time intervals, or produce periodical and alternate sounds with different frequencies.

SUMMARY OF INVENTION

An object of the present invention is to provide an electronic timepiece with a signalling device which produces a comfortable time signalling sound at a predetermined time with accurate time intervals.

Another object of the present invention is to provide an electronic timepiece with a time signalling device wherein the time signalling device produces periodical and alternate sounds with different frequencies.

An electronic timepiece with a time signalling device according to the present invention comprises a divider including a plurality of counting-down devices connected in a cascade manner for dividing a high frequency signal from a standard oscillator into a standard time signal of low frequency, and a switching device for operating said time signalling device at a set time, one of the output signals with a predetermined frequency produced from one of the output terminals of said counting-down devices being selectively applied to said time signalling device, thereby producing a time signalling sound with an audible frequency. The counting-down device may be, for example, a bistable multivibrator for dividing the frequency of a signal into half the frequency.

Further, a plurality of output signals with a predetermined frequency produced from the output terminals of said counting down devices are periodically and alternately applied to said time signalling device under the control of signal produced from one of the output terminals of said counting-down devices, thereby producing a time signalling sound with a plurality of tones.

BRIEF DESCRIPTION OF DRAWING

In the drawing:

FIG. 1 is a block diagram showing an arrangement of an electronic timepiece with a time signalling device according to one embodiment of the present invention; and

Figs. 2 and 3 are block diagrams showing an arrangement of an electronic timepiece with a time signalling device according to another embodiment of the present invention.

DETAILED DESCRIPTION

In FIG. 1 there is shown a circuit diagram wherein a quartz oscillator 10 produces a time signal of high frequency which is successively divided into a signal of

half the frequency by flip-flop circuits $FF_1, FF_2, \dots, FF_n$ in a divider 11. The divided output signal generated from the divider 11 is applied to a time counter 12 for counting time signals for seconds, minutes and hours (and including if desired, a date or day). Further, the output signal generated in the counter 12 is applied to a display means 13 including a decoder and driver to display time. The circuit further includes a signal time memorizing register 18, an electronic switch controlling circuit 17 by which an electronic switch S_1 is closed when the output generated from the counter 12 coincides with that from the register 18, and a time signalling device 16 comprising an amplifier 14 and a speaker 15.

In order to signal the time at a predetermined time, input signals containing the time signals to be signalled are applied to the register 18 for setting the time to be signalled. When the counter 12 counts the time signals to the set time, the electronic switch S_1 is closed due to operation of the electronic switch controlling circuit 17. One of the output signals having a predetermined frequency which is produced from the standard oscillator 10 and then divided by the divider is selectively applied to an input of the time signalling device 16 for producing a signal sound with a predetermined audible frequency. The frequency of the signal generated from the quartz oscillator is, for example, 2^{14} Hz (=16,384 Hz), and thus an audible frequency from 2^{13} Hz (=8,192 Hz) to 2^7 Hz (=128 Hz) may be utilized as the signal for the time signalling sound.

Therefore, for example, the output frequency signals required for the time signalling sounds may be selected from the flip-flop circuits $FF_1, FF_2, FF_3, FF_4, FF_5, FF_6$ or FF_7 (FF_4, FF_5, FF_6, FF_7 not being shown in FIG. 1).

In FIG. 2, there is shown another circuit diagram used in an electronic timepiece with a time signalling device according to the invention. When the counter 12 counts the time signals to the set time, the electronic switch S_1 is closed due to operation of the electronic switch controlling circuit 17. Therefore, the output signal generated from a time signal controlling circuit 19 is applied to an input of time signalling device 16 comprising an amplifier 14 and a speaker 15. The time signal controlling circuit 19 receives the signals of output frequencies a and b generated from flip-flop circuits FF_2 and FF_3 of the divider 11. Further, the time signals controlling circuit 19 receives the output signal generated from the flip-flop circuit FF_n of the last stage of the divider 11. Therefore, the output signal of circuit 19 is alternately supplied with frequency a or b in response to the periodical switching selection due to the output signal of the last stage of the divider 11. The frequency of the output signal a from the flip-flop circuit FF_2 is, for example, 2^{12} Hz (4,096 Hz) while the frequency of the output signal b from the flip-flop FF_3 circuit is 2^{11} Hz (2,048 Hz) when the oscillator 10 produces, for example, an output signal of frequency 2^{14} Hz (16,384 Hz).

Further, when the output signal from the flip-flop FF_{14} circuit is used as the input signal to the time signal controlling circuit 19, the output signal from circuit 19 is 1 Hz in frequency. As a result, due to the switching operation of the output signal from the last stage of the circuit 19 with the frequency of 1 Hz, the output signal from the flip-flop circuit FF_2 is generated for $t_b=1$ sec and the output signal from the flip-flop circuit FF_3 is

generated for $ta=1$ sec, as shown, and these output signals are applied to the time signalling device 16.

For example, in the above-mentioned circuit, if the input signal to be applied to the time signalling device is extracted from adjacent flip-flop circuits, two kinds of time signalling sound differing by one octave are periodically and alternately produced by the speaker.

Further, two kinds of sounds corresponding to the C tone and M tone of a musical scale are easily obtained by selecting output signals from the divider, whereby it is possible to produce a very beautiful and comfortable sound therefrom.

In FIG. 3, there is shown another embodiment in which a 3-abc counting-down circuit including flip-flop circuits FF_{n+1} and FF_{n+2} is connected to the output of circuit FF_2 so that signals of the frequencies 4,096/3 Hz and 4,096/2 Hz appear on the terminals a and b , respectively. The frequency ratio of 2 to 3 produces the time signalling sound with an interval of C and M, thus making a perfect 5-degrees music interval. Sound composed of tones of this interval is very comfortable and beautiful. It is noted that the signalling sound is so selected that the signals from the terminals a and b are changed by only alternately but also in any other desired mode by selecting the control terminal in the divider 11.

Furthermore, the control signal applied to the time signal controlling circuit 19 can be changed in frequency by switching the output terminal and flip-flop circuit of the divider (for example, from the output terminal d of the flip-flop FF_n to the output terminal c of the flip-flop FF_{n-1}), thus insuring the production of various kinds of sounds. Moreover, it will be appreciated that the electronic switch controlling circuit shown operates the electronic switch S_1 to signal at a predetermined time.

As mentioned above, the time signalling device according to the invention brings about many advantages as follows: signal sounds having a different kind of audible frequency can be selected according to the use mode because the time signal is selected from suitable output terminals of flip-flop circuits in the divider. A stable time signalling sound can be obtained because of the use of a frequency generated from a quartz oscillator. Further, it is possible to signal exactly the time to be signalled after the closing of the electronic switch because the time is memorized by the signal time memorizing register. Further, any combination of two or more output signals having a desired frequency can be periodically and alternately generated from the divider under control of the output signal produced from any

other terminal of the divider for application of the signal to the time signalling device.

What is claimed is:

1. An electronic timepiece including a time signalling device and comprising a standard oscillator for generating a high frequency signal, a divider coupled to said oscillator and including a plurality of counting-down devices connected in cascade for sequentially and respectively dividing the high frequency signal from the standard oscillator into a plurality of different intermediate frequencies and into a standard time signal of low frequency, and a switching device for operating said time signalling device at a set time and for applying one of the frequencies produced by said counting-down devices selectively to said time signalling device thereby producing a time signalling sound with an audible frequency.

2. An electronic timepiece according to claim 1, wherein each said counting-down device is a bistable multivibrator for dividing the frequency applied thereto in half.

3. An electronic timepiece according to claim 1, wherein said divider includes a plurality of output terminals connected to at least some of said counting-down devices and means by which the frequencies produced at said output terminals are periodically and alternately applied to said time signalling device under control of a signal produced from one of the output terminals of said counting-down devices, thereby producing a time signalling sound with a plurality of tones.

4. An electronic timepiece according to claim 3, wherein two output signals produced at two output terminals adjacent of said counting-down devices are periodically and alternately applied to a time signalling device, thereby producing a time signalling sound with two tones which are one octave different in frequency from each other.

5. An electronic timepiece according to claim 1, wherein said oscillator is a quartz oscillator.

6. An electronic timepiece according to claim 1, wherein said counting-down devices are flip-flop connected in series.

7. An electronic timepiece according to claim 1, comprising a counter and display means connected in series to said divider.

8. An electronic timepiece according to claim 1, comprising register means and switch controller means coupled to each other, said switch controller means being coupled to said switching device.
